[57] CLAIM

The ornamental design for a main cap stud girdle, as shown and described.

DESCRIPTION

FIG. 1 is a top view of the girdle of the invention; FIG. 2 is a front view of the article shown in FIG. 1; FIG. 3 is a back view of the article shown in FIG. 1; FIG. 4 is a bottom view of the article shown in FIG. 1; FIG. 5 is a right-side view of the article shown in FIG. 4; FIG. 6 is a left-side view of the article shown in FIG. 4; and, FIG. 7 is a perspective front view of the article shown in FIG. 1, in situ on an internal combustion engine.

The broken line showing of an engine block is for illustrative purposes only and forms no part of the claimed design.
